APPARATUS FOR IMPLANTING HAIR IN
MANIKINS, DOLLS, AND THE LIKE

John J. Mann, Milwaukee, Wis., and James A. McDonnell, New York, N. Y., assignors to Mazeko Enterprises, Inc., New York, N. Y., a corporation of New York

Application October 29, 1949, Serial No. 124,305

11 Claims. (Cl. 132—56)

1

The present invention relates to a machine for implanting human, animal or artificial hair into the scalp area of dolls, manikins, hairdresser's models and the like, or into the body of toy animals, or more generally for inserting any stranded material, such as, hair, fibres, yarns, threads, etc., into any yieldable body or substance.

Heretofore, it was customary to apply the hair to dolls or manikins in the form of wigs. These wigs were made separately, with the hair woven, sewn, ventilated or glued onto a cloth or netting foundation; it has also been proposed to make such wigs upon an elastic rubber skull piece. The wigs were then glued upon the head of the dolls or manikins, or they were formed in such manner as to remain in position upon the head by virtue of the elasticity of the foundation which frictionally engaged the head.

The resulting effect of such wigs, made in any of the aforescribed manners, is far from satisfactory in that they fail to achieve the natural appearance of hair growing normally from the scalp. The hair line of a wig is hard and artificial in appearance, and there is no similarity between the scalp area of a wig and that of a human scalp. These facts prevent the hair of such dolls or manikins from being parted or dressed like that of a person. Another defect of such wigs is that it is difficult to wash them and keep them sanitary without loosening the wig from the head, e. g. by softening the glue by which it is fastened thereto, and without causing deterioration of the foundation of the wig.

A further disadvantage of a wig is that, in any attempt to comb the hair thereof, the edges of the wig and of its foundation or skull piece cause the teeth of the comb to be caught, thus leading to a tearing of the foundation, loss of hair and eventual destruction of the wig during normal hairdressing operations. Ordinary combing to the foundation is not possible without loosening the weft, tearing the foundation or opening the sewing stitches by which the hair is fastened to the foundation.

In co-pending applications Serial Nos. 743,712, filed April 24, 1947, and 80,152, filed March 8, 1949, both now abandoned, and Patent No. 2,253,635 there have been disclosed methods of manually implanting hair into the scalp or body of dolls, etc.

An object of the present invention is to provide a machine for quickly, cheaply and efficiently performing the impaling steps.

Another object of our invention is to provide a machine for impaling hair into the skull or

2

body of a doll, manikin, toy animal or the like on a mass production basis.

A further object of this invention is to provide a machine having means for implanting a relatively large number of strands of hair at closely spaced locations into a body or skull element in a single operating cycle.

Still another object of the invention is to provide a machine having means for simultaneously forming a relatively large number of closely spaced tufts of hair on a body or skull element, each tuft consisting of a relatively large number of strands of hair.

In order to fulfill the object of implanting the strands at closely spaced locations, the use of a number of relatively thin tools or needles is indicated. Lest one or more of these needles break with each impaling stroke, it is required that the skull or body piece designed to receive the hair be rigidly supported and that movements thereof be prevented immediately before and after as well as during its penetration by the implanting needles. It is, therefore, yet a further object of the instant invention to provide, in a machine of the character described, means for satisfying the above requirements.

A still further object of our invention is to provide, in a machine of the character described, means for turning aside the strands of hair implanted in an immediately preceding impaling stroke, thereby preventing entanglement between strands during subsequent strokes.

Yet another object of this invention is to provide, in a machine of the character described, means for holding a large number of strands of hair in such manner that they will more or less automatically position themselves for successive entrainment by the needles and implantation into the surface of an article to be adorned thereby.

It is also an object of our invention to provide, in a machine of the character set forth, automatic feed means for substantially continuously supplying hair, fibre or other strands to an implanting mechanism.

Furthermore, it is an object of this invention to provide, in combination with an implanting mechanism and automatic feed means thereof, means for brushing or combing the strands to reduce their tendency to tangle or mat during the implanting process.

A related object of the present invention is to provide means for holding the strands during implanting under light tension so as further to prevent tangling and matting thereof.

A yet further object, allied with the preceding

ones, is to provide means for properly coordinating the feeding and implanting operations in a machine of the character described.

The above and other objects of the invention will become apparent from the following description of a preferred embodiment, reference being had to the accompanying drawing in which:

Fig. 1 is a front elevation of a machine according to the present invention;

Fig. 2 is a view similar to Fig. 1 but shows the machine at a different stage of operation;

Fig. 3 is a top plan view of the machine shown in Figs. 1 and 2;

Fig. 4 is a side elevation of the machine;

Fig. 5 is a rear elevation of the machine;

Fig. 6 shows a support for a doll head to be operated upon by the machine illustrated in Figs. 1-5;

Fig. 7 is a top plan view of part of the support shown in Fig. 6;

Fig. 8 is a side elevation of the part shown in Fig. 7;

Fig. 9 is a view similar to Fig. 6, showing a different type of support;

Fig. 10 is a view similar to Figs. 6 and 9, showing a still further type of support;

Fig. 11 is a side elevation, on a larger scale, of the lower extremity of a needle used in the machine of Figs. 1-5;

Fig. 12 is a front elevation of the needle portion shown in Fig. 11;

Fig. 13 is a bottom plan view of the needle;

Fig. 14 is a timing diagram showing the coordination between various elements of the machine;

Fig. 15 is a top plan view of a modified form of machine according to the invention, having means for automatically feeding strands of hair, fibre or the like to the implanting mechanism;

Fig. 16 is a sectional elevation taken on the line 16-16 of Fig. 15;

Fig. 17 is a front elevation of the implanting mechanism shown in Figs. 15 and 16, drawn to a larger scale;

Fig. 18 is a section taken on the line 18-18 of Fig. 15; and

Fig. 19 is a circuit diagram of the operating mechanism of the machine shown in Figs. 15 through 18.

Referring to Figs. 1 through 5, there is shown a machine 20 comprising a platform 21 above which rises a frame 22, the latter supporting a pair of cross beams 23a, 23b, carrying a motor 24, a speed reducer 25 and various movable parts, subsequently described, which are driven from the motor 24 through the intermediary of the speed reducer 25.

The motor 24 may be of any suitable construction but is here shown as a type in which a driving sprocket 26, linked by a chain 27 with a driven sprocket 28 mounted on the input shaft 29 of the speed reducer, can be clutched to the motor shaft by means of an operating arm 30, pivoted at 31, to which a lever 32 is secured which links the arm 30 with a suitable pedal or handle (not shown).

The output shaft 33 projects from the speed reducer 25 on two sides, carrying a cam 34 and a disc 35 on one extremity and a bevel gear 36 on the other. Mating with the bevel gear 36 is a similar gear 37, having twice the number of teeth of the former, which is fixed to a vertical shaft 38 carrying at its lower end a flusher member 39, this member being in the form of a bent rod having extremities 39a and 39b.

A vertical piston 40, reciprocably mounted in

a bearing block which is formed by members 41a, 41b secured to the cross beams 23a, 23b, is linked with the disc 35 by means of a connecting rod 42 which is eccentrically pivoted to the disc at 43. The lower end of piston 40 carries a set of needles 44 which are aligned in the direction of shaft 33, as clearly seen in Fig. 4. Referring to Figs. 11, 12 and 13, each needle 44 is formed at its underside with a saddle 45 toward which converge two flutes 46, 47, corresponding flutes of all the needles being aligned with one another. These needles are in register with an aperture 48 formed in a tray 49, passing through this aperture when the piston 40 is in its lowermost position (Fig. 2) and being clear of the tray when the piston rises to the top (Fig. 1).

The tray 49, as best seen in Fig. 4, is controlled by the cam 34 through a follower rod 50 the forked upper end of which is held in continuous engagement with the cam by a pair of contracting springs 51, 52, the springs being anchored at the top to an arm 53, which rests on the housing of speed reducer 25, and at the bottom to a plate 54 secured to the rod 50. Plate 54 is also secured to the tray 49 through the intermediary of a stud 55 and is held for vertical oscillations by a guide rod 56, the latter being slidable in a bearing block formed by members 41b, 41c and 41d.

The article to be adorned with hair, shown here as a doll's head 60, is mounted on the platform 21 by means of any one of three supports 61 (Fig. 6), 62 (Fig. 9) and 63 (Fig. 10). Each support has a base 64 and an arm 65 which may be vertical as in the case of support 61, inclined as in the case of support 62 or horizontal as in the case of support 63. The arm 65 terminates at the top in a vertical socket portion 66 adapted to receive a shoe or anvil 67, the latter having a shank 68 and a slot 69 as best seen in Figs. 7 and 8. As illustrated in Fig. 1, in which the support 61 has been shown in operating position by way of example, the support is fixed to the platform 21 (by any suitable means, not shown) in such a position that the slot 69 of its anvil 67 is aligned with the needles 44. It may be mentioned at this point that support 61 serves for implanting hairs at the top of the skull piece 60, support 63 for implanting hairs in the region of the occipital hair line, and the support 62 for implanting hairs in an intermediate zone. The use of a plurality of separate, fixed supports in lieu of a single, adjustable one is preferred on account of the greater rigidity of these individual supports, this rigidity being desirable in order to prevent snapping of the needles during the operating process about to be described.

A bundle of hairs 70 (Fig. 1) is placed on the tray 49 longitudinally of the latter, that is, in a direction transverse to the row of needles 44, in such manner as to overlie the aperture 48 of the tray. Next the lever 32 is actuated to clutch the sprocket 26 to the shaft of motor 24, resulting in the rotation of flusher member 39 and in an oscillatory movement of tray 49 and of piston 40. These movements are illustrated in the diagram of Fig. 14 in which the top curve represents the rise and fall of piston 40, the center curve the movement of tray 49 and the bottom curve the rotation of flusher rod 39. Owing to the transmission ratio of 2:1 at the bevel gears 36, 37, shaft 38 carrying rod 39 rotates at half the speed of shaft 33 carrying cam 34 and disk 35, so that rod 39 rotates through 180° during each reciprocatory cycle of the members 40 and 49. The positive peaks 39a in Fig. 14 indicate the aligned

position of extremity 39a with aperture 48 while the negative peaks 39b denote the corresponding position of extremity 39b.

From Fig. 14 it will be seen that the descent of the tray 49 somewhat precedes that of piston 40 carrying needles 44; this tray, owing to its inherent springiness, resiliently bears upon the skull piece 60 when in its bottom position which it occupies for an extended period, on account of the provision of a flat or concentric portion 34a (Fig. 1) on cam 34. During this period, when the member 60 is firmly pressed against its support 61, the needles 44 penetrate the surface of this member and enter the slot 62, at the same time entraining some of the strands of hair forming part of the bundle 10. It will be understood that these strands in penetrating the shell 60 form a loop around the fluted ends of the needles, the loops expanding after penetration because of the inherent resiliency of the hair. Owing to this immediate expansion the strands remain anchored to the skull 60 after the needles have been withdrawn, an upward movement of the skull piece to follow the needles 44 being prevented by the tray 49 which at this time still occupies its lowermost position, as clearly apparent from Fig. 14.

Immediately after the tray has risen, an extremity of the flusher member 38, say, the end 38a, passes between the tray and the skull piece 60, this being the position illustrated in Fig. 4. The passage of either end of the rod 39 sweeps aside all strands of hair which have been anchored in the piece 60, and which at this time still extend upwards through the aperture 48, thereby withdrawing these strands from the tray 49 and clearing the aperture 48 for the next impaling operation. Owing to the adhesion between the strands 10, and also because these strands are interwoven or matted to a certain extent, this action will draw a new group of hairs toward the center of the tray 49 and, thereby, into alignment with the needles 44. The operator, meanwhile, slightly rotates the piece 60 on the support 61 so that during the next cycle a new set of strands will be impaled in a row somewhat spaced from the strands previously implanted.

Referring, now, to Figs. 15 through 18, there is shown a machine comprising an implanting mechanism or press, generally indicated at 120, and in combination therewith a feed mechanism generally indicated at 80. The elements of the press 120 are somewhat similar to those of the machine 20, shown in the preceding figures, and include a standard or frame 122 having an upper or supporting portion 123 on which there is mounted a driving motor 124. A piston 140 is reciprocably held in the frame portion 123 and is linked by means of a connecting rod 142 to a disc 135 to which the rod 142 is pivoted at 143. Disc 135 is mounted on a shaft 133 which is aligned with the shaft 129 of motor 124, being coupled thereto by means of a slipping clutch 81. Shaft 133 is supported on the frame portion 123 by means of a bearing post 82.

The feed mechanism 80 comprises a generally circular table 83 borne by legs 84a and secured to the press body 122 by means of brackets 84, 85, 86. Rotatably supported on the table 83 is a feeder ring 88 having a number of arcuate slots 89 which are separated by bridges 90, the latter being only long enough to insure mechanical stability. The slots 89 are aligned with the plunger or piston 140 which on its lower extremity car-

ries an extension 91, the latter holding a row of needles or punches 144 extending in the general direction of these slots and adapted to penetrate the latter as well as an aligned slot 92, provided in the table 83, when the pivot 143 of disc 135 is in its lowermost position.

Each of the slots 89 is flanked on both sides by arcuate rows of pins 93 designed to receive between them the strands of hair, fibre or the like, indicated at 170, which are to be implanted by the needles 144 into an object, not shown, positioned underneath the slot 92. The feeder ring 88 is bounded on the outside by a rubber ring 94 and on the inside by a similar rubber ring 95, an annular rack 96 (with its teeth facing downwards) being inserted between the members 88 and 95. Rollers 97, pivotally secured to the top of table 83, engage the inner ring 95 to center the feeder ring 88 relative to the table 83.

10 The ring 88 with its adjacent members 94, 95 and 96 is supported on the table 83 by means of rollers 98 journaled in grooves 99, 100 of the ring 88, as best seen in the left-hand portion of Fig. 16. The teeth of rack 96 are engaged by a 15 pinion 101 which is driven, over gears 102, 103, from a motor 104 supported on table 83.

A third motor 105, secured to the underside of table 83, drives a pair of pulleys 106, 107 mounted on shafts 108, 109, respectively, these shafts 30 being inclined toward each other so as to form a V the apex of which points against the direction of rotation of the ring 88. These shafts, journaled in bearings 110, 111 which are mounted on an angle plate 112, secured to the underside of table 83, and on the table 83, respectively, carry a pair of comb or brush rollers 113, 114 rotating in the direction indicated by the arrows; these brush rollers, therefore, are adapted to comb outwardly any strand of hair or the like which 35 is fed past them by the pins 93. It should be noted that the strands 170, owing to the forward movement of the ring 88, will assume an inclined position when engaged by the rollers 113, 114, the inclination being such as to align these 40 strands substantially with the planes in which the said rollers rotate. As best seen in Fig. 18, the rollers 113, 114 are closely adjacent respective flanks of the ring 88, so that their bristles or teeth 115 will part and straighten out all the 45 strands 170 moving toward the press 120. A wheel 116 of soft rubber freely rotates on a shaft 117 which is secured to the angle plate 112 and to a similar, smaller plate 118 rising from the 50 table 83, wheel 116 bearing resiliently upon the 55 strands and preventing them from rising above the pins 93 when engaged by the bristles 115.

Turning now more particularly to Figs. 16 and 17, it will be seen that a set of staggered soft rubber wheels 151 bear upon the outer surface of annular strip 94, these wheels being supported by shafts 152 from frame portion 123. Similarly, a set of staggered soft rubber wheels 153, supported by shafts 154 from a bracket 155 which in turn is secured to the frame 122, bear upon the surface of the inner annular strip 95. The cooperation between these strips, which 60 preferably also consist of soft rubber or equivalent material, and the wheels 151, 153 exerts a slight tension upon the depending extremities 70 of strands 170, hanging down on both sides of ring 88, when these strands are engaged by the descending needles 144, thus tending to prevent tangling or matting during the impaling operation.

It will be understood that there are various

ways in which the descent of the plunger 140 may be synchronized with the rotation of ring 88 in such manner that the plunger will not operate as long as the needles 144 are aligned with one of the bridges 90 and that, preferably, the rotation of ring 88 is halted whenever the needles penetrate the slots 89, 92. As shown in the embodiment illustrated, movement of piston 140 is normally prevented by means of an escapement mechanism which includes a pawl 156 which cooperates with a disc 157 secured to the shaft 133, this disc having a peripheral notch 158 which is engaged by pawl 156 whenever the piston is in its top position. Pawl 156 is pivoted at 159 to a pair of brackets 160, 161 rising from the frame portion 123. An operating rod 132 is pivotally linked to the pawl 156 at 162 and is similarly linked at 163 to a pedal 164, the latter being biased upwardly by a spring 165 and being pivoted to the frame 122 at 166. It will be seen that momentary stepping upon the forward end of pedal 164 will disengage the pawl 156 from the notch 158 of disc 157, thus allowing the shaft 133 to make one full revolution and to effect a single descent and ascent of the plunger 140 and of the needles 144.

Depending from the pawl 156 is a rod 167 which maintains closed a pair of contact springs 168, 169 as long as the pawl is in engagement with the notch 158, these contacts being thus open whenever the plunger 140 is out of its normal or top position. Another set of contacts is shown at 170, 171; the latter are closed whenever the plunger 140 is aligned with one of the slots 89 and are opened when the needles 144 register with one of the bridges 90. For this purpose there is pivoted to the periphery of table 83, at 172, an arm 173 carrying at one end a cam follower roller 174 and having its other extremity engaged by a tension spring 175 which, being anchored to a bracket 176 secured to the underside of table 83, urges the roller 174 against the underside of ring 88. This underside is provided with a series of spaced cams 177, of a length somewhat exceeding that of the bridges 90 and equal to them in number (six in the embodiment illustrated), these cams being so positioned as to depress the roller 174 whenever a bridge 90 overlies the slot 92 in table 83. When this occurs, a lug 178 depending from arm 173 depresses the contact spring 171, thus breaking the connection between contacts 170, 171.

Referring now to the circuit diagram of Fig. 19, it will be seen that the motor 105, which drives the brush rollers 113, 114, is continuously energized from a source 179 which may be direct or alternating current power mains. The energizing circuit for motor 104, which rotates the ring 88, is not completed unless contacts 168, 169 are closed; since these contacts are open whenever the plunger 140 is not in its home position, it will be understood that operation of the pedal 164 will momentarily arrest the ring 88 while the plunger 140 and, with it, the needles 144 descend to perform their impaling or implanting operation. When the plunger has reverted to the top, after one or several complete revolutions of shaft 133 (depending on how long the pedal 164 is held depressed), the contacts 168, 169 are reclosed and rotation of the ring 88 (in the clockwise direction indicated by the arrow in Fig. 15) is resumed.

The energizing circuit for motor 124, which drives the shaft 133 by way of the slipping clutch 81, includes the contacts 170, 171 which, as set

forth above, are closed only when one of the slots 89 is aligned with the needles 144. Thus it will be seen that, regardless of whether or not the operator steps on pedal 164 when a solid or bridge portion 90 is underneath these needles, the plunger will not descend in such a position, so that damage to the machine through negligent operation will be avoided. At the same time the operator retains full control of the rate at which the plunger is actuated, so that the object on which the implanting process is to be performed can be accurately positioned before each working stroke. It may be mentioned that means to hold the object in place during impaling, analogous to the moving tray 49 of Figs. 1 through 5, may be provided also on the machine just described.

It is to be understood that the invention is not limited to the specific embodiment shown and described but is, on the contrary, capable of numerous modifications and adaptations without departing from its spirit or exceeding its scope as defined in the objects and in the appended claims.

We claim:

1. A machine for implanting material in a penetrable article, said machine comprising a reciprocating piston, implanting tool means secured to said piston, a support for said piston, and a carrier member movable past said support in a direction perpendicular to said piston, said carrier member being provided with a slot adapted to register with said tool means in certain positions of said carrier member, said piston being operable to effect penetration of said slot by said tool means, first drive means for actuating said piston, second drive means for displacing said carrier members, a first energizing circuit for said first drive means, and a second energizing circuit for said second drive means, said first energizing circuit being operative when said carrier member is in said certain positions.

2. A machine according to claim 1, comprising contact means opening said second energizing circuit when said slot is penetrated by said tool means.

3. The combination, with a machine according to claim 1, of rotating comb means coacting with said carrier member to straighten out material carried by said carrier member, said comb means being positioned ahead of said piston.

4. The combination according to claim 3 wherein said comb means comprises a pair of oppositely rotating rollers positioned on opposite sides of said slot.

5. The combination according to claim 4, comprising an additional roller of soft, resilient material bearing upon said carrier member intermediate said oppositely rotating rollers.

6. The combination, with a machine according to claim 1, of pressure means resiliently bearing upon said carrier member on opposite sides of said piston, said presser means being adapted to engage and apply light tension to strands engaged by said tool means.

7. A machine according to claim 1, comprising a row of spaced pins rising from said carrier member on each side of said slot.

8. A machine for implanting material in a penetrable article, said machine comprising a vertically reciprocating piston, implanting tool means secured to the lower end of said piston, a support for said piston, and a horizontal feed ring rotatable past said support underneath said piston, said feed ring being provided with at least

one arcuate slot adapted to register with said tool means in certain positions of said feed ring, and rows of spaced pins rising from said feed ring on opposite sides of said slot.

9. A machine according to claim 8, comprising a pair of annular strips of yieldable material bounding said feed ring on the inside and on the outside, and presser rollers respectively bearing upon said annular strips adjacent said piston, said presser rollers being adapted to engage and apply light tension to strands engaged by said tool means.

10. The combination, with a machine according to claim 8, of a combing device comprising a pair of oppositely rotating rollers positioned on opposite sides of said slot close to said feed ring and an additional roller of soft, resilient material being from above upon said feed ring intermediate said oppositely rotating rollers.

11. The combination according to claim 10, 20

wherein said oppositely rotating rollers are inclined relative to the radial direction of said feed ring, the axes of said rollers forming a V the apex of which points against the direction of rotation of said feed ring.

JOHN J. MANN.

JAMES A. McDONNELL.
